CURTAIN AND METHOD OF MAKING SAME

Roswell I. Bosworth, Cranston, R. I., assignor to
 Guyan Mills, Inc., a corporation of Rhode
 Island

Application November 26, 1934, Serial No. 754,819

4 Claims. (Cl. 156—10)

This invention relates to a textile curtain, more particularly that type known as a "cottage set"; and this invention has for one of its objects the provision of horizontal stripe effects particularly 5 in the border in a curtain of this character when woven in a single shuttle loom.

Another object of the invention is the provision 10 of a fabric which may be used for "cottage sets" throughout widely varying widths of windows, without the necessity of wasting any of the fabric, and without the necessity of weaving fabrics to a variety of varying widths for accommodating windows of different widths.

Another object of the invention is the provision 15 of a curtain in a single shuttle loom, which will have contrasting colored stripe effects particularly in the border running horizontally of the curtain, which heretofore could have been produced only in box looms employing a plurality 20 of shuttles, which is far more expensive and complicated to operate.

With these and other objects in view, the invention consists of certain novel features of construction, as will be more fully described, and 25 particularly pointed out in the appended claims.

In the accompanying drawing:

Fig. 1 is an elevation looking at the inside of a window with curtains illustrating my invention as mounted in position over the window.

Fig. 2 is a top plan view of a piece of fabric 30 from which these curtains are made.

Fig. 3 is a plan view of the upper pair of curtains.

Fig. 4 is a plan view of the lower pair of curtains.

Fig. 5 is a plan view of the tie backs severed from the lower pair of curtains.

Heretofore, in the provision of what is known 40 as "cottage sets" of curtains, in order to produce these curtains inexpensively, it has been customary to weave them on a single shuttle loom. It is also customary to hang curtains with the warps extending vertically and the filling threads extending horizontally and curtains so made were 45 cut across the warp threads that the desired lengths might be produced, their widths being relatively fixed by the width of the fabric woven. Further, it was necessary to either accept as the width of the curtain the width of the fabric as 50 woven or to split the fabric in two, using one half for one side and the other half for the other side of a pair of curtains, or it was necessary to waste a portion of the fabric if it were cut between the middle and one edge. Further any striping or 55 contrasting effect appeared in a vertical manner

in the warps as the single shuttle could not give contrasting weft effects. Heretofore, in order to produce any horizontal strip or contrast in color or design it was considered necessary to produce such a curtain fabric in a box loom with a plurality of shuttles, where the shifting of the shuttles is accomplished each carrying a different filling and which is a much more expensive operation. Thus this condition of affairs limited the design effects which could be produced in 5 curtains in a simple single shuttle loom and made it necessary to weave many varying widths of material for the accommodation of windows of varying widths and practically made it necessary for one buying curtain goods by the yard to waste 10 a certain portion of these goods, if the desired width could not be obtained, which was a frequent condition.

The length of "cottage sets" is well standardized and in order that a new range of effects may 15 be produced in a simple manner, such as horizontal stripe effects particularly in the border, I have woven the goods from which "cottage sets" are to be made of a width equal to the standard length of the "cottage sets" with the idea in 20 mind that the warp threads shall run horizontally and the filling threads vertically; and in this manner I may cut the curtains of any desired width for the accommodation of either narrow or extremely wide windows and may obtain 25 a horizontal stripe effect of color or other contrasting border appearance by variation of the warp threads in a single shuttle loom.

And I have further found that by adopting this 30 method of procedure I may cut from the fabric one of the borders in the curtain, which is to be used on the lower part of the window and I can use this portion for the so-called "tie backs" for the upper portion of the curtains, thereby giving 35 a harmonizing blend of color which is so carefully worked out in the color scheme of the fabric I may produce; and the following is a more detailed description of the present embodiment of this invention illustrating the preferred means by 40 which these advantageous results may be accomplished:—

With reference to the drawing, 10 designates 45 a sheet of fabric as it comes from the loom. The warp threads are extending in the direction of the arrow 11 with the filling threads at right angles to them. This fabric is woven on a single shuttle loom so that the filling threads are all of the same character and present the same appearance wherever they show. The warp threads, however, which are led from the warp beam or 50

several warp beams, may be of contrasting appearance, either because of different colors, different sizes, different materials or any other manner of causing these warp threads to be of contrasting appearance, so that I form stripes 12 by means of the contrasting warp threads which extend lengthwise of the fabric and while they may be varied throughout a wide range, I usually choose to provide a marginal or border stripe 13 at one edge and a marginal border stripe 14 at the other edge of the fabric and as one of these edges becomes the lower edge, a hem at the lower edge of the curtain is unnecessary as the stripe or border effect will afford the desired decoration.

15 Cottage-set curtains are standardized at a definite length or width, the upper pair of curtains being approximately 45 inches and the lower pair 36 inches long. Accordingly, the fabric which I weave is made of a width substantially 48 or 49 inches which fills the requirement as to the length of the upper pair and I sever from this width of fabric enough to provide for the dimension of the lower pair and utilize this severed portion for the tie-backs.

25 To provide the upper pair of curtains for the set, I cut a piece of fabric across the warp threads so that the warpwise length or extent of the fabric after hemming will be equal to the width of the curtain desired, and as shown in Fig. 3 this 30 width which runs warpwise of the curtains is designated x , and would be formed by severing the piece of fabric 10 in Fig. 2 at the dotted line 26.

The hem of these curtains is formed warpwise, as at 15, by doubling the border 13 back 35 upon itself and sewing as at 16 and 17 to provide a rod pocket 18. I may then dispose a curtain rod thru this pocket 18 for mounting the curtain in position. By causing the hem to run warpwise of the fabric the striping formed by the 40 contrasting warp threads is disposed horizontally of the fabric, while the filling threads are disposed vertically and a curtain having a horizontal stripe effect is produced by the use of but a single shuttle loom. A finishing hem 19 is also formed 45 at the edges of the curtains while a hem at the lower selvage edge is optional, it being merely necessary in some instances to turn back one-half inch and bind the narrow selvage.

The lower pair of curtains, designated 20 in 50 Fig. 4, are formed by similarly severing the piece of goods, such as at the dotted line 26 and in the case of the lower pair there is a cutting off of substantially nine inches of the border, such as the border 13 shown in Fig. 2, after which a hem is produced at the upper edge by doubling the 55 fabric upon itself, as at 21, and sewed at 22 and 23, providing a rod pocket 24 thru which the curtain rod is passed for hanging the curtain in position.

60 The side edges are also provided with hems, while the bottom selvage edge may, optionally, be provided with a hem, or the narrow portion doubled back and sewed.

The severed portions 27 from the curtains are 65 doubled back upon themselves and stitched as at 28 so as to provide the so-called "tie-backs" which are provided with rings 29 and are looped about the upper pair of curtains as at 30, see Fig. 1, to hold these curtains in the desired pulled-back 70 position.

In this manner, I provide a curtain on a single shuttle loom with a horizontal striping or border effect from goods in the piece which may be sup-

plied in a manner to be cut off at any desired length to provide a curtain of the desired width, without any waste of material. Accordingly, a new effect in curtains may be produced by a simple and inexpensive single shuttle loom which has heretofore been produced only by a much more complicated procedure.

5 It will be understood that any desired weave can be used in these fabrics which I produce.

By the term "cottage set" I will be understood 10 to mean primarily four pieces of material; that is, two upper curtains, two lower curtains, and in some cases may additionally include two tie backs for the upper curtains.

15 The foregoing description is directed towards the method and construction illustrated, but I desire it to be understood that I reserve the privilege of resorting to all the equivalent changes to which the construction and method are susceptible, the invention being defined and limited 20 only by the terms of the appended claims.

I claim:

1. The method of forming a cottage set which consists in providing a fabric having a woven contrasting border along at least one marginal edge thereof extending warpwise of the fabric cutting from the fabric across the warp threads a plurality of pieces of material with the warpwise extent substantially equal to the width of each curtain, cutting a strip warpwise from the pieces 25 to become the lower pair of curtains, hemming both the upper and lower pairs of curtains with the hems extending warpwise and causing the curtains to hang with the warp threads extending horizontally to provide a horizontal border effect 30 at the lower edge and utilizing the severed strip for the tie backs for the upper pair of curtains.

2. The method of forming a cottage set which 35 consists in providing a fabric having a woven contrasting border at the opposite marginal edges extending warpwise of the fabric, cutting from the fabric a plurality of pieces of material with the warpwise extent substantially equal to the width of the curtain, cutting warpwise one border 40 from the pieces to become the lower pair, hemming both the upper and lower pairs of curtains with the hems extending warpwise and causing the curtains to hang with the warp threads extending horizontally to provide a horizontal 45 border effect, and utilizing the severed border for tie backs for the upper pair of curtains.

3. A cottage set which comprises upper and lower woven fabric curtains each having the warp threads extending horizontally and a hem at their upper edge extending warpwise of the fabric, a border along the lower marginal edge comprising warp threads of an appearance contrasting with the warp threads in the main portion of the body of the fabric, and tie backs for the upper pair of curtains corresponding with a portion of said curtains.

4. A cottage set which comprises upper and lower woven fabric curtains each having the warp threads extending horizontally and a hem at their upper edge extending warpwise of the fabric, a border along the lower marginal edge comprising warp threads of an appearance contrasting with the warp threads in the main portion of the body of the fabric, and tie backs for the upper pair of curtains corresponding with the border of said curtains.

ROSWELL I. BOSWORTH.
